(57) CLAIM

The ornamental design for a hands free device for a portable phone, as shown and described.

DESCRIPTION

FIG. 1 is a perspective view of a hands free device for a portable phone showing our design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view thereof with a wrist band shown in broken lines to illustrate environment.

The broken lines shown in FIG. 8 illustrate environmental structure and form no part of the claimed design.
